UNITED STATES PATENT OFFICE.

MICHAEL KAHNE, OF NEW YORK, N. Y.

STIFFENING DEVICE FOR SOFT COLLARS.

1,266,274.

Specification of Letters Patent. Patented May 14, 1918.

Application filed November 10, 1917. Serial No. 201,859.

To all whom it may concern:

Be it known that I, MICHAEL KAHNE, a citizen of Russia, and a resident of New York, county and State of New York, United States of America, have invented certain new and useful Improvements in Stiffening Devices for Soft Collars, of which the following is a specification, reference being had to the accompanying drawings, forming a part thereof.

My invention relates to stiffening devices for soft collars and to the construction of collars for use with this device. The object of the invention is to provide a collar construction and a simple device for maintaining the collar in proper form so that it will present a good appearance.

Another object is to make the device removable, so that it will not interfere with the washing of the collar.

A still further object is to so construct the device so that it may be used to hold the front corners of the collar raised for the purpose of facilitating the application of a necktie.

In order that my invention may be thoroughly understood I will now proceed to describe the same in the following specification, and then point out the novel features thereof in appended claims.

Referring to the drawings:

Figure 1 is a front elevation of a collar constructed in accordance with my invention and having my improved stiffening devices applied thereto.

Fig. 2 is a rear end elevation of the front part of one end of a collar with the band folded up, showing the construction of the collar and illustrating the manner in which the stiffening device is inserted therein.

Fig. 3 is a front elevation of the collar with its front edges raised and the open loops at the ends of the transverse part of the stiffening devices hooked together.

Figs. 4 and 5 are elevations of the two stiffening devices.

Fig. 6 is a view similar to that of Fig. 4 showing the form of stiffening device when it is to fit a collar with curved front edges.

Like characters of reference designate corresponding parts in all the figures.

10 designates a collar, in this case constructed of soft material. On its under side near the front edges of the collar are pockets 11 open at the top as at 12.

13 designates other pockets which may be

provided on the collar, if desired, spaced from the pockets 11. The band of the collar is designated 14.

The stiffening device is constructed of a single piece of stiff wire and comprises a straight shank 20, a bend 21, another shank 22 spaced from but parallel with the shank 20 and a transverse portion 23. The upper end of the shank 22 is affixed to the transverse portion at 24 in some suitable manner such, for example, by soldering it thereto. The other end of the transverse portion is constructed to form a loop 25 open at 26 for a purpose which will appear hereinafter.

The portion formed of the parallel shanks 20-22 is adapted to be inserted in the pocket 11 and the transverse portion 23 which is curved to fit the contour of the upper edge of the collar is adapted to fit under the fold thereof. When the pockets 13 are provided they assist in holding this transverse portion 23 in position.

The operation of the device as thus described, is obvious and may be understood by referring to Fig. 1. The stiffening devices are light and effectively hold the front edges and lower corners of the collar in the desired position without inconveniencing the wearer because they are made of resilient material and perform their function without adding any material rigidity to the collar.

Another use of the device is illustrated in Fig. 3. In this case the transverse portions 23 are removed from the pockets 13 and turned over when the corners of the pockets are in a raised position to meet each other, and the loops 25 thereof are hooked together. While in this position the stiffening devices will hold the front corners of the collar up so as to facilitate the application of a necktie. After this the loops 25 are unhooked and the transverse portions 23 slipped under the fold of the collar to perform the function previously described.

The device of Fig. 6 is similar to that shown in the preceding figures, but in this case the parallel wires 20¹ and 22¹ are curved to correspond with the shape of the collar with which it is to be used, it being understood of course that the pocket into which this part of the device fits, is similarly curved. In either case the parallel wire shank of the stiffeners fit tightly in their pockets, their resiliency permitting them to spring together enough to insure a substantially rigid connection.

What I claim is:

1. A soft fold collar, pockets on the under-side thereof near and parallel with the inner edges of the collar open at the top, combined with stiffening devices, each constructed of resilient wire having a portion of separated and parallel parts of the wire adapted to fit tightly into said pockets, and a transverse curved portion adapted to fit under the fold 10 of the collar.

2. A soft fold collar, pockets on the under-side thereof near and parallel with the inner edges of the collar open at the top, combined with stiffening devices, each constructed of wire having a portion of separated and parallel parts of the wire adapted to fit tightly into said pockets, and a transverse curved portion adapted to fit under the fold 15 of the collar, said transverse portions terminating in open loops adapted to be hooked together.

3. A soft fold collar, pockets on the under-side thereof near and parallel with the inner edges of the collar, open at the top, and 20 other pockets spaced therefrom on the under-

side of the collar, combined with stiffening devices, each constructed of wire having a portion of separated and parallel parts of the wire adapted to fit tightly into said edge 25 pockets, and a transverse curved portion adapted to be inserted in said other pockets and to fit under the fold of the collar.

4. A soft fold collar, pockets on the under-side thereof near and parallel with the inner edges of the collar, open at the top, and 30 other pockets spaced therefrom on the under-side of the collar, combined with stiffening devices, each constructed of wire having a portion of separated and parallel parts of the wire adapted to fit tightly into said edge 35 pockets, and a transverse curved portion adapted to be inserted in said other pockets and to fit under the fold of the collar, said transverse portions terminating in open loops adapted when removed from said other 40 pockets, to be hooked together.

In witness whereof, I have hereunto set my hand this 2 day of November, 1917.

MICHAEL KAHNE.
